UNITED STATES PATENT OFFICE.

WALTER A. CLARK, OF GENEVA, NEW YORK, ASSIGNOR TO THE PHILLIPS & CLARK STOVE COMPANY, OF SAME PLACE.

DESIGN FOR A BEARING-BOX TOP FOR GEAR-ACTUATED JOURNALS OF STOVE OR RANGE GRATES.

SPECIFICATION forming part of Design No. 34,000, dated January 29, 1901.

Application filed December 26, 1900. Serial No. 41,175. Term of patent 14 years.

To all whom it may concern:

Be it known that I, WALTER A. CLARK, of the village of Geneva, county of Ontario, State of New York, have invented and produced a new and original Design for a Bearing-Box Top for the Gear-Actuated Journals of Stove or Range Grates, of which the following is a specification, reference being had to the accompanying drawing, forming a part thereof, consisting of a single figure illustrating my design in perspective.

As shown in the drawing, my design consists of the two bars A and B, arranged side by side so as to be parallel with each other, having the intervening space S and the bridge D connecting them, the latter having upon its upper surface the rib R.

The bar A has the horizontal top T' and upon its under side the concavities C' C' and the horizontal parts J'. It has at each of its ends the downwardly and inwardly projected surfaces E', each of which have a projection d and a cross-rib R² at each of the ends of the top part T'.

The bar B has the convexly-rounded ends E², the flat top parts T² between the ends, the concavities C² C² on its under side arranged to be horizontally in line with the concavities of the bar A, and the straight horizontal lower edge parts J², with the plate B, having a greater vertical depth than the bar A.

Having thus described my invention, what I claim, and desire to secure by Letters Patent, is—

The design for a bearing-box top for the gear-actuated journals of stove and range grates, as herein described and shown.

Signed at Geneva, Ontario county, New York, this 22d day of September, 1900, in the presence of the two witnesses whose names are hereto written.

WALTER A. CLARK.
